UNITED STATES PATENT OFFICE.

JULIUS GOLON, OF SUFFIELD, CONNECTICUT.

TOBACCO-LEAF CONVEYER.

Application filed June 30, 1925. Serial No. 40,559.

To all whom it may concern:

Be it known that I, JULIUS GOLON, a citizen of Poland, and resident of Suffield, in the county of Hartford and State of Connecticut, have invented certain new and useful Tobacco-Leaf Conveyers, of which the following is a specification.

This invention relates to improvements in conveyers, particularly tobacco leaf conveyers, as they are, for instance described in my co-pending application, Serial No. 3414, filed January 19, 1925, and it is the principal object of the present invention to provide a conveyer adapted to receive and hold a plurality of loads and allowing a gradual lowering of those loads as for instance, tobacco leaf bunches, from storage or curing lofts to or from transporting vehicles, or the like.

Another object of the invention is the provision of a conveyer allowing a stopping and locking of the conveyer drums at predetermined points, as for instance, the superposed stories of a loft building, or the like.

A further object of the invention is the provision of a conveyer including a plurality of spring controlled cable drums, the cables on each of which are arranged in groups.

A still further object of the invention is the provision of a conveyer in which each group of cables is guided over suitable rollers, and carries the receptacles for the loads.

It is also one of the objects of the invention to provide the load receptacles of the conveyer with suitable doors finding a resting place on one of the walls thereof.

These and other objects and advantages of my invention will become more fully known as the description thereof proceeds, and will then be specifically defined in the appended claims.

In the accompanying drawing forming a material part of this disclosure:

Fig. 1 is a side elevation of a conveyer constructed according to the present invention.

Fig. 2 is a front elevation of the device.

Fig. 3 is a section on line 3—3 of Figure 1.

Fig. 4 is a top plan view of the device.

The conveyer illustrated on the drawing comprises a frame 10 supporting a shaft 11 on which a plurality of drums, as shown

two, 12 and 13, are rotatably arranged. Within these drums, springs 14 and 15 are arranged having their inner ends secured to shaft 11 as at 16, while their outer ends are attached to the inner walls of the drums, as at 17.

The upper cross bar of the frame is equipped with a hanger 18 or other suitable means, for suspending the conveyer from a suitable support, for instance a rafter of a tobacco storing house or loft, etc.

Cables 19 and 20 of suitable material and length are wound upon the drums in two series or groups for each drum, 21, 21' and 22, 22', and these cables are guided over suitable rollers 23, 23' and 24, 24' in extensions 25 and 26 of the frame. The outer ends of each group of cables carry frames or receptacles for the reception of the loads, each comprising a bar 27 having a shouldered lower end 28 and a bar 29, to the lower end of which a plate 30 is hinged, as at 31, adapted to swing inwardly and to rest with its outer end upon the shoulder 28.

The depending side bars of the frame carry latches 32 and 33 sliding in suitable guide sockets 34 and 35 and having upper handles 36 and 37.

The outer ends of shaft 11 are equipped with sockets 36' and 37' rotating with the drums carrying plates 38 and 39 having a plurality of recesses 40 adapted to receive the lower ends of the latches allowing a stopping and locking of the conveyer at predetermined points.

The operation of the device will be entirely clear from the above description without further explanation, and it will be understood that changes may be made in the general construction and arrangement of the minor details thereof, without departure from the spirit of the invention.

Having thus described my invention what I claim as new and desire to secure by Letters Patent, is:

1. In a tobacco leaf conveyer, a plurality of rotating spring controlled drums, groups of cables on each drum, frames at the ends of said cables, each comprising a straight bar and a shouldered side bar, a lower bar pivotally attached to said straight bar and

adapted to rest upon the shoulder of said side bar allowing insertion of a load into said frame and closing of the bottom thereof.

2. In a tobacco leaf conveyer comprising a plurality of rotating spring controlled drums, a shaft for said drums, sleeves on said shaft and drums, recessed discs at the ends of said sleeves, a hanger for said con-

veyer, a pair of latches guided on said hanger adapted to engage in the recesses of said discs for stopping the rotation of said drums at certain predetermined points. 10

Signed at Suffield in the county of Hartford and State of Connecticut this 19 day of June A. D. 1925.

JULIUS GOLON.
